(57) **CLAIM**

The ornamental design for a storage bed, as shown and described.

DESCRIPTION

FIG. 1 is a top, front and left side perspective view of a storage bed showing our new design; FIG. 2 is a bottom, rear and right side perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is a top, front and left side perspective view showing the storage bed in a first raised position; FIG. 10 is a bottom, rear and right side perspective view showing the storage bed in the first raised position; FIG. 11 is a top, front and left side perspective view showing the storage bed in a second raised position; FIG. 12 is a bottom, rear and right side perspective view showing the storage bed in the second raised position; FIG. 13 is an enlarged view of portion 13 in FIG. 2; and, FIG. 14 is an enlarged view of portion 14 in FIG. 2. The broken lines in the drawings illustrate portions of the storage bed which form no part of the claimed design.

1 Claim, 14 Drawing Sheets
